UNITED STATES PATENT OFFICE.

WILLIAM J. KEENE, OF CHICAGO, ILLINOIS, ASSIGNOR TO CHICAGO SPRING BUTT COMPANY, OF CHICAGO, ILLINOIS, A CORPORATION.

SPRING-HINGE.

1,111,158.

Specification of Letters Patent.

Patented Sept. 22, 1914.

Application filed August 23, 1912. Serial No. 716,784.

To all whom it may concern:

Be it known that I, WILLIAM J. KEENE, a citizen of the United States, and a resident of Chicago, county of Cook, and State of Illinois, have invented certain new and useful Improvements in Spring-Hinges, of which the following is a full, clear, and exact description.

The invention relates to double-acting spring hinges for doors or the like, and more particularly to spring hinges which are adapted to be mounted in a recessed corner of the door and are provided with a longitudinally movable, spring actuated bolt which co-operates with studs or rollers fixed to the floor plate or hinge post to yieldingly hold the door in central position.

The invention seeks to provide a simple effective construction of this sort which can be economically manufactured and consists in the features of improvement hereinafter set forth, illustrated in the preferred form in the accompanying drawings and more particularly pointed out in the appended claims.

In the drawings, Figure 1 is a longitudinal section of the improved hinge shown as applied to the door. Fig. 2 is a horizontal section on the line 2-2 of Fig. 1. Fig. 3 is a plan view of the floor plate. Fig. 4 is an inverted plan view of the adjustable collar.

The frame of the improved hinge preferably comprises a single bar 10 of strap iron or steel, which is provided at one end with a downturned portion 11. The opposite end of the frame bar and the end of the portion 11 are provided with upwardly and horizontally projecting extinctions 12 and 13, respectively, by which the hinge is secured in position to the door. As shown, the hinge is adapted to be set within a recess 14 cut in the lower corner of the door 15. The extinctions 12 and 13 fit within grooves or rabbets formed in the side and bottom edges of the door and are fastened thereto by screws 16. The other hinge member comprises a plate 17 which rests upon the floor 18 and is adapted to be fixed in position in any suitable manner. In the form shown, the plate is provided with holes 19 arranged to receive screws 20.

The floor plate is provided with an upwardly projecting circular boss 21. A finishing plate 22 of thin sheet metal fits over

the plate 17 and is held in position by the screws 20. This plate is provided with an opening through which the boss 21 projects. A pivot bolt 23 extends through an opening 24 in the boss 21 and is rigidly secured to the floor plate, preferably by upsetting its lower end. The upper end of the pivot bolt is journaled in a bushing 25 which fits snugly within an opening in the frame bar 10. Preferably, the bolt is provided with an enlarged upper end or head 26 which overlaps the upper face of the frame bar. As shown, the door is provided with a recess 27 to receive the head 26.

A collar 28 rests upon and is adjustably secured to the boss 21 of the floor plate and is provided with an opening through which the pivot pin or bolt extends. In the preferred construction shown, the boss 21 is provided with an upwardly projecting lug 29 which is arranged within a recess 30 in the collar 28, and a pair of adjusting screws 31 are threaded through the portions of the collar on opposite sides of the recess. These screws engage the lug 29 to hold the collar against movement, but by adjusting the screws, the collar may be adjusted above the pivot bolt 23.

The upper face of the collar 28 is provided with a circular flange 32 within which sets a concaved ring 33 and a series of balls 34 are interposed between the ring and the lower flanged end of the bushing 25. The anti-friction bearing thus formed sustains the weight of the door.

The spring actuated plunger 35 of the hinge is arranged within a coiled spring 36 and is provided with a forked inner end, the arms 37 of which extend within the horizontally disposed guiding recess 38 formed in the collar 28 between its upper and lower portions. The portions of the collar above and below the recess 38 are connected by the walls of the recess 30 and by an integral part 39 arranged in front of the pivot bolt 23. Studs 40 extend between the upper and lower portions of the collar 28 and across the recess 38. These studs are arranged on opposite sides of the pivot bolt 23 and are arranged to co-operate with the arms 37 of the spring plunger. Preferably, the studs are provided with rollers 41 which are engaged by the arms 37.

The inner end of the spring 36 engages a flange 42 on the plunger and the outer end 43

of the spring engages an adjusting nut 43 which is threaded on a stem or bolt 44, the latter being fixed to and projecting inwardly from the end portion 11 of the frame 5 bar 10.

When the door is swung in one or the other direction, the frame of the hinge swings therewith about the pivot bolt 23. The spring plunger swings about one or the 10 other of the eccentric studs 40 so that the spring 36 is compressed and acts, when the door is released, to return the door to normal central position. If the door is swung to a wide open position or more than 90° 15 from its closed position, the spring plunger will act to hold it open. By adjusting the screws 31, the hinge frame can be adjusted on the pivot bolt 23 to accurately aline the door in central position. The hinge frame 20 and operating parts are preferably inclosed in a pair of finishing plates 45 which are secured to the door by screws 46. The rear inturned edges of these plates are overlapped by a finishing plate 47 which is secured in position by the screw or screws 16 25 which pass through the extension 12 of the hinge frame.

It is obvious that numerous changes may be made in the details set forth without 30 departure from the essentials of the invention as defined in the claims.

I claim as my invention:

1. A spring hinge comprising a hinge frame, adapted to be seated in the recessed 35 corner of a door, a floor plate, a pivot bolt uniting said frame and floor plate, a collar loosely mounted on said bolt and comprising integral upper and lower portions with an intermediate horizontal recess, studs 40 fixed at their ends to the upper and lower portions of said collar and extending across said recess on opposite sides of said bolt, rollers journaled on said studs and within said recess, a spring actuated plunger having 45 arms at its inner end extending within said recess and engaging said rollers, and adjustable connections between said floor plate and said collar for adjustably rotating the latter on said pivot bolt.

2. A spring hinge comprising a frame 50 adapted to be seated in the recessed corner of a door, a floor plate, a pivot bolt fixed at its lower end to said plate, journaled in said frame and uniting the same to said 55 floor plate, a collar interposed between said floor plate and said frame, said floor plate having a vertical projecting stud extending into the recess in said collar, adjusting screws threaded through the side walls of 60 said recess and engaging said lug, studs carried by said collar on opposite sides of said bolt, and a spring actuated plunger in said frame having arms coöperating with said studs, substantially as described.

3. A spring hinge comprising a single

frame bar adapted to be secured in the recessed corner of a door, a floor plate, a pivot bolt fixed to said plate, and journaled in said frame bar and having a headed end 70 above the same, a collar on said bolt between said frame bar and said floor plate, studs carried by said collar on opposite sides of said bolt, and a spring-actuated plunger having arms coöperating with said studs, substantially as described.

4. A spring hinge comprising a single frame bar adapted to be secured in the recessed corner of a door, a floor plate, a pivot bolt fixed to said plate, and journaled in said frame bar and having a headed end 80 above the same, a collar on said bolt between said frame bar and said floor plate, said collar having an upturned circular flange, a bushing in said frame bar about said bolt, a ball bearing arranged within 85 the planes of said collar and engaging said bushing, studs carried by said collar on opposite sides of said bolt, and a spring-actuated plunger having arms coöperating with said studs, substantially as described.

5. A spring hinge comprising a single frame bar adapted to be secured in the recessed corner of a door, a floor plate, a pivot bolt to said plate, and journaled in said frame bar and having a headed end above 90 the same, a collar on said bolt between said frame bar and said floor plate, a bushing in said frame about said bolt, said collar having a circular flange on its upper face, a concave ring within said flange, bearing 95 balls interposed between said ring and said bushing, studs on said collar on opposite sides of said bolt, and a spring actuated plunger having arms coöperating with said studs, substantially as described.

6. A spring hinge comprising a single frame bar having a downturned portion at one end and vertical and horizontal extensions whereby it is secured in position, a floor plate, a collar interposed between said floor plate and frame bar, a pivot bolt fixed to said floor plate and extending through said collar and said frame bar, said bolt having a head engaging the upper face of said frame bar, said collar having a horizontal recess and vertical studs extending across said recess on opposite sides of said bolt, a spring actuated bolt connected at its outer end to the downturned portion of said frame bar and having arms at its inner 115 end extending into the recess of said collar and engaging said studs, and adjusting connections between said collar and said floor plate, substantially as described.

7. A spring hinge comprising a single 125 frame bar having a downturned portion at one end and vertical and horizontal extensions whereby it is secured in position, a floor plate, a collar interposed between said floor plate and frame bar, a pivot bolt hav-

- ing a headed upper end and extending through said frame bar and collar and fixed at its lower end to said floor plate, a ball bearing interposed between said collar and said frame bar, adjusting connections between said collar and floor plate, studs carried by said collar on opposite sides of said bolt, and a spring actuated plunger having arms coöperating with said studs.
- 5 8. A spring hinge comprising a single frame bar having a downturned portion at one end, said bar and said end portion having vertically and horizontally projecting extensions respectively for fastening the frame to the door, a floor plate, an adjusting collar interposed between said frame bar and said floor plate and resting on the latter, a pivot bolt extending through said frame bar, collar and floor plate and connecting said parts, a plunger having a forked inner end, said collar having a horizontal guiding recess between its upper and lower portions for the arms of the forked end of said plunger, studs arranged in the recess of said collar on the opposite sides of said pivot bolt and coöperating with the arms of said plunger, a spring coiled about said plunger an adjusting support for the outer end of said spring mounted on the downturned end portion of said frame bar, and adjust-
- ing devices directly connecting said floor plate and said collar for rotatably adjusting the latter about said pivot bolt, substantially as described.
9. A spring hinge comprising a single frame bar, having a downturned portion at one end and vertical and horizontal extensions whereby it may be secured in position in the recessed corner of a door, a floor plate, an adjusting collar resting on said floor plate, a ball bearing interposed between said collar and said frame bar, a pivot bolt extending through said frame bar, ball bearing, collar and floor plate and uniting said parts, a plunger having a 45 forked inner end, said collar having a horizontal guiding recess and studs arranged therein on opposite sides of said pivot bolt, a spring actuated plunger having forked arms at its inner end extending within the 50 recess of said collar and engaging said studs, and adjusting connections between said floor plate and said collar for rotatably adjusting the latter about said pivot bolt, substantially as described.
